UNITED STATES PATENT OFFICE

GEORGE I. GOLDWYN, OF CHICAGO, ILLINOIS, ASSIGNOR OF ONE-HALF TO HERMAN GOLDWYN, OF CHICAGO, ILLINOIS

METHOD OF TREATING USED BURLAP BAGS

Application filed September 5, 1929. Serial No. 390,493.

This invention relates to an improved method of treating used burlap bags and it consists of the matters hereinafter described and more particularly pointed out in the appended claims.

The primary object of the invention is to provide a method whereby used burlap bags may be treated to fit them for further commercial use.

10 Another object of the invention is to so treat a used burlap bag that its usually exposed edges are secured against ravelling or fraying.

These objects of the invention as well as others together with the many advantages thereof will more fully appear as I proceed with my specification.

In the drawings:—

Fig. 1 is a perspective view of a used burlap bag after having been treated in accordance with my improved method.

Fig. 2 is a transverse sectional view through the seam of a new burlap bag before the bag is turned with the outside out.

25 Fig. 3 is a transverse sectional view through the seam of Fig. 2 after the bag has been turned to bring the outside out.

Fig. 4 is a perspective sectional view through the seam of a used bag after having been treated in accordance with my improved method.

With the demand established in the business world for good, strong, low cost burlap bags, many industries have been built up around the treating of used burlap bags to restore them to a condition adapting them for re-use. Such bags are cleaned and the seam rips and fabric holes are stitched or sewn so as to effectively hold the commodities with which they are filled in re-use.

40 Certain established laws prohibit the re-use of such bags with the original brand or trade-mark relating to the original contents exposed to view, so that it has been the practice to turn the bags inside out, whereby said brand or trade-mark is in effect obliterated. Such a practice also permits a better cleaning of the burlap fabric and a more complete removal of the lint which accumulates near 45 the stitched seam, due to the ravelling and

fraying of the marginal edges of the fabric beyond the associated stitching.

The fabric from which burlap bags are made is comparatively loose woven and is usually made from jute fibers. Such fabric 55 quickly ravelles and frays at its cut edges and forms lint which sloughs off so that it tends to disintegrate.

In forming a burlap bag, a piece of fabric of twice the area of a finished bag is cut from 60 a bolt of such burlap fabric usually salvaged along both margins and this piece is folded upon itself to form the opposite side walls 1 and 2 respectively of the bag to be made as best shown in Fig. 1.

65 In stitching the cut fabric into bag form, a margin 1^a and 2^a respectively of each wall of the bag is turned back upon the bag fabric and a line of stitching 3 is then run along one side and one end of the folded bag fabric 70 to form one of the closed sides and the bottom of the bag. Thus the stitching passes through four thicknesses of fabric as shown in Fig. 2. The stitched and folded bag blank is then turned to bring the outside out as shown in 75 Fig. 3 and this brings the margins 1^a and 2^a on the inside of the bag. The bag then will be ready for filling, and its open top is closed in any desired manner.

80 After the original contents have been emptied from the bag, the empty bag which has heretofore been considered as an economic waste, is now saved and is turned inside out and is thoroughly cleaned and repaired where needed and then it takes its place for sale as 85 a reconditioned used bag.

85 In reconditioning the bag it is re-turned inside out and is generally suction cleaned and this removes all content and dust particles from the bag and removes all lint from 90 the seams. With the bag re-turned inside out such brands and trade-marks which originally appeared on the outside of the bag are now on the inside and are therefore obliterated.

95 After the bag has been re-turned inside out, it brings the margins 1^a and 2^a upon the outside of the bag again, just in the position they were in when they were first stitched together. The edge portions 1^b and 2^b respectively 100

tively of said margins, outwardly beyond the line of stitching 3 are usually ravelled and present a frayed appearance to the bag. This frayed or ragged appearance detracts from the resale value of the bag when sold for re-use in this condition and such frayed edges will eventually slough off as lint, up to said line of stitching which could easily pull through the fabric under bag load with the result that 10 the bag would open up at points along said line of stitching.

To overcome the objections noted I fold over said edge portions 1^b and 2^b respectively, back upon said margins to cover up said line 15 of stitching 3 and then gather in the frayed ends of the warps and wefts thereof and secure said parts together in any suitable manner. I find one convenient manner of doing this is to run the stitched margins of the bag 20 through a sewing machine equipped with suitable folders to fold over said frayed ends of the warps and wefts and then stitch the bag parts together by an overcast stitch 4 as best shown in Fig. 4. This overcast stitch 25 passes through the bag fabric along a line 4^c spaced inwardly from the folded over margins and the loops 4^b of said overcast stitch pass about said folded over margins and binds or secures said frayed ends in place.

30 Thus an overcast seam is provided for the bag, which reinforces the original line of stitching 3 and the frayed ends of the marginal parts 1^b and 2^b respectively, are gathered in and bound in place so that a good 35 strong and neat seam is provided for the bag which greatly enhances its resale value.

By my improved method, I am enabled to put a used burlap bag in a better condition for re-use and I am enabled to restore such 40 bags as have heretofore been discarded as waste into a condition suiting them for further re-use, then has been possible in methods heretofore employed.

45 While in describing my improved method, I have referred in detail to the various steps, and to the sequence thereof, the same is to be considered merely as illustrative so that I do not wish to be limited thereto except as may be specifically set forth in the appended 50 claims.

I claim as my invention:—

1. The method of treating used burlap or like bags which consists in providing a bag 55 turned inside out to expose the folded over margins of the bag fabric and the frayed edges thereof as well as the line of stitching securing said folded over margins together, in folding over the frayed edges of the margins back upon said line of stitching to cover the same and then securing said frayed edges to the unfrayed parts of said margins.

2. The method of treating used burlap or like bags which consists in providing a bag 60 turned inside out to expose the folded over

margins of the bag fabric and the frayed edges thereof as well as the line of stitching securing said folded over margins together, in folding over the frayed edges of the margins back upon said line of stitching to 70 cover the same and providing a second line of stitching adjacent said margins to secure said frayed edges to the unfrayed parts of said margins.

3. The method of treating used burlap or like bags which consists in providing a bag 75 turned inside out to expose the folded over margins of the bag fabric and the frayed edges thereof as well as the line of stitching securing said folded over margins together, 80 in folding over the frayed edges of the margins back upon said line of stitching to cover the same stitching the bag fabric together adjacent said margins with an over cast stitch which binds the frayed edges to the unfrayed 85 parts of said margins.

In testimony whereof, I have hereunto set my hand this 29th day of August, 1929.

GEORGE I. GOLDWYN.
